UNITED STATES PATENT OFFICE

JOHN F. O'CONNOR, OF CHICAGO, ILLINOIS, ASSIGNOR TO W. H. MINER, INC., OF CHICAGO,
ILLINOIS, A CORPORATION OF DELAWARE

ANTIFRICTION BEARING

Application filed August 24, 1928. Serial No. 301,833.

One object of the invention is to provide an anti-friction side bearing, especially adapted for railway cars, including a roller element interposed between the usual body and truck bolsters of the car, wherein the roller element is automatically centered after each actuation thereof by cooperating means on the bolsters controlled by relative angular movement thereof, including a vertically 10 slidable element having engagement with the roller to center the same.

Another object of the invention is to provide a roller side bearing for railway cars, having means for centering the roller automatically upon relative movement of the bolsters and wherein the adjustment of the centering means is not affected by relative adjustment of the bolsters toward or away from each other.

Other and further objects of the invention will more fully appear from the description and claims hereinafter following.

In the drawing, forming a part of this specification, Figure 1 is a vertical sectional view through portions of the body and truck bolsters of a railway car, illustrating my improvements in connection therewith, the anti-friction element being shown in both its centered position and the position assumed at the end of its travel in one direction. Figure 2 is a top plan view of the bearing member shown in Figure 1, the body bolster being omitted in this view. And Figure 3 is a vertical, transverse sectional view, corresponding substantially to the line 3-3 of Figure 1.

In said drawing, 10 denotes the underside portion of the body bolster of a railway car and 11 the upper portion of the opposed truck bolster.

My improved anti-friction bearing comprises, broadly, a retaining housing A; an anti-friction roller element B; a centering slide C; a bottom bearing plate support D; a body bolster bearing plate E; and a truck bolster bearing plate F.

The body bolster bearing plate E is in the form of an elongated thick plate which is narrower than the housing A, as most clearly shown in Figure 2. The plate E has the

corners thereof cut away, as clearly shown in Figure 2, and is secured directly to the bottom of the body bolster 10 by means of a pair of rivets 12-12 at the opposite ends thereof, the rivets being shown as disposed on the axial center line of the plate.

The housing A is in the form of a substantially rectangular box-like member, open at the top and bottom and having opposed, longitudinally extending vertical side walls 13-13 and vertical end walls 14-14. The end walls 14 are cut away, as indicated at 15, at the upper ends thereof, to accommodate the bearing plate E. Immediately below the cutaway portions 15, the walls 14 are provided with outstanding horizontal lugs 16-16 by which the housing is secured to the bearing plate E, each lug being preferably provided with a pair of securing rivets 17-17 which extend through the bearing plate E. The side walls 13 of the housing A are provided with guide openings 18-18 for a purpose hereinafter described, the guide openings being in transverse alignment.

The bearing plate support D is of generally rectangular outline and has a centrally depressed pocket portion 19 in which the bearing plate F is seated. The bearing plate F, as shown, is preferably secured to the supporting plate D by a pair of rivets 20-20 which are countersunk so that the heads will not protrude above the top surface of the bearing plate. The supporting plate D is fixed to the top of the truck bolster by means of two rivets 21-21 at the opposite ends of the plate, as most clearly shown in Figure 1. At opposite sides, the central portion of the plate D is provided with cam tracks 22-22, each cam track, as shown, comprising two inclined cam surfaces, the meeting, high point of which is substantially at the transverse center of the bearing plate F and the supporting plate D. As most clearly illustrated in Figure 1, the cam tracks 22 extend below the top surface of the main body portion of the supporting plate D and the side edges of the plate D are cut away at opposite ends of the plate to provide horizontal ledges 23 which merge with the lower end

90
95
100

portions of the inclined surfaces of the cam tracks 22.

The anti-friction element B is in the form of a solid roller which is directly supported 5 on the bearing plate F of the truck bolster and, as shown in Figure 3, has the upper portion thereof enclosed within the housing A. The roller B is adapted to have cooperating 10 rolling action with the bearing plates E and F of the body and truck bolsters during relative angular movement of these bolsters about the center bearing of the car.

The centering slide C is also in the form of a hollow box-like member, open at the top 15 and bottom, and has longitudinally extending vertical side walls 24-24 and transverse end walls 25-25. The slide C is of such a size as to fit within the housing A for substantially free vertical sliding movement, being guided by the side and end walls of the 20 housing, which cooperate with the corresponding walls of the slide. To limit the downward movement of the slide, each side wall 24 thereof is provided with a laterally 25 outwardly extending horizontal lug 125 which works within the opening 18 of the corresponding side wall 13 of the housing A. As will be evident, the downward movement of the slide C will be positively limited by 30 engagement of the lugs 125 with the bottom walls of the guide openings 18 of the housing. The purpose of limiting the movement of the centering slide C, with respect to the housing, is to prevent loss or separation of 35 the parts while being handled in shipment or while being handled during application of the parts to the body and truck bolsters of the car.

The anti-friction roller B is housed within 40 the centering slide C and, as shown in Figure 3, is of greater length than the width of the plate F and has the opposite ends thereof spaced slightly from the inner faces of the side walls 24 of the slide. The side 45 walls 24 of the slide have in-turned sections 26 formed at the lower ends thereof, the in-turned sections 26 having supporting guide surfaces 27 which are inclined upwardly from the center of the slide, as most clearly 50 shown in Figure 1. The inclined surfaces 27 merge with the inner surfaces of the end walls 25 of the slide C, as most clearly shown in Figure 1, the inner surfaces of the walls 25 being curved, as indicated at 28. The 55 central sections of the curved surfaces 28 of the walls 25 are cut away, as indicated at 29, so that the anti-friction roller will be held free of the surfaces 29 by engagement with the surfaces 28 at the opposite sides of the 60 walls 25. The walls 24 of the slide embrace the sides of the bearing plate E, and the end walls 25 are cut away at the top end portions thereof, as indicated at 30, so as to clear the bearing plate E when the slide is raised 65 to the highest point. The side walls 25 are

also cut away at the bottom ends thereof, as indicated at 31-31, so that the same will clear the bearing plate F of the truck bolster when the slide moves to the extreme limit of its downward movement. 70

The side walls 24 protrude beyond the end walls of the slide C and also beyond the bottom of the housing in the normal position of the parts, as clearly shown in Figure 1. The bottom edges of the side walls are inclined upwardly from the center, as clearly 75 shown in Figure 1, thereby presenting oppositely inclined cam surfaces 32-32 which cooperate with the cam tracks 22 of the bearing plate support D. 80

In the normal position of the parts, when the body and truck bolsters are in vertical alignment, the roller is disposed centrally of the housing and the truck bolster bearing plate F, resting on the latter, and the centering slide C has the central portion of the inclined bottom edges of the side walls resting on the high points of the cam tracks 22 of the supporting plate D. With the parts in this position, the opposite end sections of 90 the roller B rest lightly upon the central portions of the inclined centering surfaces 27 of the slide C. In the normal position of the parts, before approach of the body and truck bolsters toward each other, the top surface of the roller B is spaced a substantial distance from the bearing surface of the plate E of the body bolster, as clearly shown in Figures 1 and 3. 95

In assembling the side bearing, the slide 100 C is inserted through the top of the housing and then the roller B is dropped in position within the slide also by being passed through the upper part of the housing. The housing is then secured to the bearing plate E by 105 means of the rivets 17, thereby permanently closing the top of the housing and preventing loss of the roller and centering slide.

The operation of my improved side bearing is as follows: When the body and truck 110 bolsters approach each other, the bearing plate E will engage the top surface of the roller B and upon relative angular swinging movement of the body and truck bolsters, the roller B will be rolled along the opposed bearing surfaces of the body and truck bolster bearing plates E and F. During the relative angular movement of the bolsters, the slide C will move downwardly, due to the inclination of the cooperating surfaces 115 32 and 22 on the slide and the bearing plate support D. As will be evident, during the downward movement of the slide the inclined centering surfaces 27 of the slide will 120 recede from the bottom of the roller. In Figure 1, the roller B is shown in dotted lines in two positions, namely, the centered position and the position at the extreme left-hand end of its movement. 125

Upon return swinging movement of the 130

bolsters, the slide C will be forced upwardly by the cam tracks 22 and the inclined centering faces or surfaces 27 on the slide C will engage the roller, thereby forcing the same to roll to the centered position shown in Figure 1.

As will be evident from the preceding description taken in connection with the drawing, I have provided a side bearing, the principal parts of which are attached to the body bolster, thereby leaving the bearing plate of the truck bolster unobstructed at its edges so that no foreign matter may accumulate on the same which will interfere with the proper operation of the roller bearing element. A further advantage obtained by my design of improved side bearing is that the adjustment of the centering means is not effected by relative adjustment between the body and truck bolsters of the car. It is frequently found necessary in railway practice to adjust the space between the body and truck bolsters either by inserting shims between the parts of the center bearing or removing shims therefrom. As will be evident, as the body bolster is elevated or lowered with respect to the truck bolster, the slide C will be adjusted freely within the housing A and will always maintain a constant relation with respect to the truck bolster and especially the top bearing surface of the plate F.

It is further pointed out that by providing the holding means on the slide C for retaining the same in assembled relation with the housing, and by supporting the roller on the ledges 26 of the slide, all the parts of the bearing are held in assembled relation and cannot be accidentally lost in handling before application to the bolsters of the car.

While I have herein shown and described what I consider the preferred manner of carrying out my invention, the same is merely illustrative and I contemplate all changes and modifications which come within the scope of the claims appended hereto.

I claim:

1. In an anti-friction side bearing for railway cars having body and truck bolsters, the combination with a movable anti-friction element interposed between the bolsters; of means for centering the anti-friction element including a vertically movable member having means thereon engaging said anti-friction element to center the same; guide means on one of said bolsters for guiding said member for vertical movement at right angles to said bolster and carrying said member bodily laterally with the bolster in unison therewith; and an actuating element on the other bolster engaging with said member to reciprocate the same along said guide means on the cooperating bolster upon relative angular movement of said bolsters.

2. In an anti-friction side bearing for rail-

way cars provided with body and truck bolsters, the combination with a movable anti-friction element interposed between the bolsters and adapted to have rolling engagement therewith; of a slide cooperating with the anti-friction element to center the same; means on one of said bolsters for guiding the slide for vertical movement in a path at right angles to said bolster; and separate means on the other bolster engaging said slide and actuating the same in said vertical direction upon relative angular movement of the bolsters.

3. In an anti-friction side bearing for railway cars provided with body and truck bolsters, the combination with a roller element interposed between the bolsters; of a housing secured to one of said bolsters and enclosing the roller; sliding means guided within the housing while being carried laterally bodily with said bolster for centering the roller; and cooperating engaging means on the sliding means and the other bolster for actuating the sliding means to displace the latter with respect to the first named bolster upon relative movement of said bolsters to center the roller.

4. In an anti-friction side bearing for railway cars having opposed body and truck bolsters, the combination with an anti-friction roller element interposed between the bolsters; of a centering slide having means thereon for centering said element when the slide is actuated; means on one of said bolsters for guiding the slide; and cooperating cam means on the other bolster and slide for actuating the latter upon relative angular movement of said bolsters.

5. In an anti-friction side bearing for railway cars having opposed body and truck bolsters, the combination with an anti-friction roller element interposed between said bolsters; of a centering slide having inclined guide faces thereon for operating with the roller to center the same upon vertical movement of said slide; rigid means fixed to each bolster respectively and moved relatively by angular movement of said bolsters, and directly engaging and actuating the slide to center the roller.

6. In an anti-friction side bearing for railway cars having opposed body and truck bolsters, the combination with a housing secured to one of the bolsters, said housing being provided with an interior bearing surface; of an anti-friction element within the housing cooperating with said bearing surface and having rolling movement thereon; a centering slide guided for vertical movement in the housing, said slide having inclined guide surfaces cooperating with the roller to center the same upon vertical displacement of the slide; and a cam track on the other bolster, cooperating with the slide

to actuate the same upon relative movement of said bolsters to center the roller.

7. In an anti-friction side bearing for railway cars, the combination with relatively angular movable opposed body and truck bolsters; of a housing secured to the body bolster; an anti-friction roller element within the housing, said roller element being supported on the truck bolster; a centering slide 10 guided for vertical movement in the housing, said slide having inclined guide surfaces cooperating with the roller to center the same; and a fixed cam track on the truck bolster on which said slide is supported.

15 In witness that I claim the foregoing I have hereunto subscribed my name this 22nd day of August, 1928.

JOHN F. O'CONNOR.
